UNITED STATES PATENT OFFICE.

WILLIAM D. MANN, OF NEW YORK, N. Y., ASSIGNOR TO MANN'S BOUDOIR CAR COMPANY, OF SAME PLACE.

RAILWAY-CAR.

SPECIFICATION forming part of Letters Patent No. 356,653, dated January 25, 1887.

Application filed March 25, 1884. Serial No. 125,451. (No model.)

To all whom it may concern:

Be it known that I, WILLIAM D'ALTON MANN, a citizen of the United States, residing at New York, in the county and State of New York, have invented certain new and useful Improvements in Boudoir Railway-Cars, of which the following is a specification.

My invention relates to improvements in railway-cars having some points in common with the improved sleeping-car described in Letters Patent No. 198,991, granted to me the 5th of January, 1878.

Under my improved construction I employ end platforms, which may be of customary form, and at each end of the car a vestibule connecting with a side corridor, and communicating with the latter any desirable number of rooms with beds athwart the car; and I also construct one or more rooms the entire width of the car, so as to cut off the side corridor or 15 corridors. Connecting with the vestibule at one end I arrange a ladies' boudoir or state-room with beds athwart the car, and also a ladies' dressing-room, which, together with the ladies' vestibule, are separated by a door from the main corridor, thus securing to ladies traveling alone a seclusion not otherwise attainable. In connection with the other vestibule I construct a buffet and smoking- 20 room and a gentlemen's toilet-room, these, together with the gentlemen's vestibule, being separated from the main corridor by a door serving to protect the main body of the car from any odor in the buffet or smoking-room.

In order to effect the ventilation of the state- 25 rooms of boudoir-cars, I construct the panels of the doors and the stationary panels above the crown-moldings of rattan, slat, cane, or other open-work, which may be made highly ornamental and affords a free circulation of air, while keeping the rooms strictly private as regards vision. I also provide sliding panels extending from the level of the seat-arms to such a height that when moved up- 30 ward the occupants of the state-rooms have uninterrupted view across the corridor and through the windows, and are thus enabled to look out freely at either side of the car. I further provide, in conjunction with the side corridor, sliding panels and beds athwart the car, doors for communication between some

or all of the adjoining state-rooms or boudoirs, so as to provide for parties traveling in company communicating rooms which may be secluded or thrown open to the corridor and the 55 entire car at the will of the occupants.

In order that my invention may be fully understood, I will proceed to describe it in detail with reference to the accompanying drawings, in which--

Figure I is a floor plan of a railway-car illustrating the invention. Fig. II is a floor plan illustrating a modification. Fig. III is a vertical longitudinal section through the corridor, looking toward the state-rooms, and showing 60 some of the rooms closed and some open. Fig. IV is a transverse section of the car. Fig. V is a perspective view of one of the sliding panels on a larger scale. Fig. VI is an elevation of the same in position in the frame, 70 also on a larger scale. Fig. VII is a horizontal section thereof, also on a larger scale.

11 represent the end platforms of the car, which connect with vestibules 23, provided with toilet and dressing rooms 45, and connecting through doors 67 with a side corridor, 8, extending a part of the length of the car. The door 6, which shuts off the ladies' vestibule 2 and dressing-room 4 from the corridor 8, also incloses and secludes a ladies' 75 boudoir, 9, opening out of the ladies' vestibule 2. A corresponding door, 7, at the gentlemen's end of the car separates the corridor 8 from the gentlemen's vestibule 3, connecting with which are a dressing-room, 5, a closet, 5^a, 80 or a buffet, 10, and a smoking-room, 11. These apartments may be optionally arranged as illustrated in Figs. I and II, and are secluded by the door 7, so as to prevent the passage of any odor to the corridor 8, and thus to 85 the main body of the car.

12 represents separate state-rooms connecting with the corridor 8. These may be of any number, according to the construction and desired capacity of the car.

I further provide a drawing-room, 13, extending the whole width of the car, which may be arranged centrally, as in Fig. II, or at or near one end, as preferred, and is isolated from the corridors by doors 13^a. When the corridor is separated by the drawing-room, these separate corridors may be on one side, as in Fig. 95

I, or on opposite sides, as in Fig. II. It will further be apparent that other parts of my invention may be carried into effect without the use of the drawing-room 13, or an apartment extending the whole width of the car.

5 In some places I have shown the state-rooms 12 double—that is, provided with two transverse couches separated by standing room—and in some places single, and I have illustrated a door, 12^a, in the partition between two rooms. Such a door may manifestly be placed in any of the partitions where it is desirable, so as to provide communicating rooms for families or parties traveling in company. 15 My arrangement of side corridors and transverse couches affords special facility for such conveniences.

The longitudinal partition which separates the corridor 8 from the state-rooms 12 is constructed above the crown-molding 14 with panels 15, of open cane or rattan work, adapted to permit the free passage and circulation of air, while precluding vision. I may employ similar open-work panels above the crown-molding over one or both of the doors 6, 7 in the transverse partitions which separate the end vestibules from the corridor; but this open-work is preferably dispensed with at the gentlemen's end of the car, so as to prevent the 30 passage of odors from the buffet and smoking room.

The doors 17 of the state-rooms are formed with panels 18 of open-work in slats or cane, rattan, or other material to permit the circulation of air, while preserving the privacy of the rooms.

In the partition between the doors 17 are double panels 19, receiving between them sliding panels 20, which extend for a sufficient 40 height above the level of the arms of the state-room seats 21 to afford to the occupants of the rooms, when the sliding panels are thrown up, a full and free view on the corridor side, and thus provide for all passengers who may desire it the same freedom as in an open car for day use, while complete seclusion may be had at night, or when desired.

In order to adapt the panels 20 to slide freely

between the partition-stiles or door-jambs, I construct them with tongues 23, short vertically, projecting horizontally at their upper and lower ends, and fitting within grooves in the stiles 22. By the use of the short tongues 23, I am enabled to guide the panels and adapt them to move freely without danger of cramping or binding, which would otherwise be liable to occur from changes of temperature or from straining or warping of the frame-work. The edges of the panels between the tongues 23 are beveled, as shown at 24 in Figs. V and VII, the beveled edges projecting within the guiding-grooves in the partition-stiles without contact, so as to completely exclude vision and at the same time to be entirely free from liability to stick. The sliding panels are provided with lifts and locks of any suitable form on the inside, enabling the occupants of the rooms to move or tightly secure the panels at their own pleasure.

Having thus described my invention, the following is what I claim as new therein and desire to secure by Letters Patent:

1. In a boudoir or other car, a partition for separating the state-room from the corridor, having one or more sliding panels in the lower portion, and rattan or other open-work above the crown-molding, as and for the purpose set forth.

2. In a boudoir or other car provided with state-rooms and a longitudinal corridor, a partition for separating said state-rooms and corridor, provided with one or more sliding panels, as and for the purpose set forth.

3. A boudoir sleeping-car having a side corridor, adjoining boudoirs fitted with beds 85 athwart the car, a connecting-door in the partition between the said boudoirs, and one or more movable panels in the partition between the couch portions and the side corridor for throwing the whole open for day use, as explained.

W. D. MANN.
